RIBBON CARTRIDGE FOR BUSINESS MACHINES

Ellen V. B. Ludwick, Syracuse, Aaron C. Zeamer, Cortland, and James E. Harmon, Groton, N.Y., assignors to SCM Corporation, New York, N.Y.

Continuation of design application Ser. No. 323,495, Sept. 15, 1973. This application Oct. 10, 1974, Ser. No. 513,912

Term of patent 14 years

Int. Cl. D18—01

U.S. Cl. D64—11 A

FIG. 1

FIG. 2

FIG. 3

FIG. 1 is a perspective view of a ribbon cartridge for business machines showing our new design:

FIG. 2 is a top plan view thereof;

FIG. 3 is a left side elevational view thereof;

FIG. 4 is a rear elevational view thereof; and

FIG. 5 is a bottom plan view thereof.

This is a continuation of application Ser. No. 323,495, filed Jan. 15, 1973.

We claim:

The ornamental design for a ribbon cartridge for business machines, as shown.
